THROTTLE CONTROL

Chester A. Killmeyer, Toledo, Ohio

Application August 10, 1932, Serial No. 628,147

4 Claims. (Cl. 123—179)

My invention relates to throttle controlling device of internal combustion engines and particularly to the type that is used during the starting period.

- 5 New improvements in internal combustion engines have made it essential that the carburetor throttle be opened further for starting than the conventional idle throttle opening. This is true particularly with downdraft carburetion.
- 10 In the combination of automatic starting switches and downdraft carburetion it is very desirable to automatically control the throttle opening during the starting period. With downdraft carburetion it is very desirable to open the throttle a certain amount beyond the conventional idle 15 throttle opening in order to start the engine quickly when it is hot. When the engine is stopped the heat stored in the manifold and other parts is conducted to the carburetor causing the fuel in the carburetor to boil or percolate. This boiling or percolation of the gasoline forces the fuel out of the carburetor nozzle into the intake manifold. A drain is usually provided to drain this excess fuel from the manifold but the hot manifold vaporizes some of the fuel and consequently the manifold is practically filled with vapor. Thus a very rich mixture is produced in the intake manifold and consequently starting is delayed due to the overly rich mixture. If the 20 engine does not start after a few revolutions of the starter the average driver will choke the engine. This enriches the mixture still more and consequently the engine will not start because of the flooded condition.
- 25 It is also desirable to have the throttle open further than the conventional idle opening for starting during cold weather. This additional throttle opening gives the engine enough power to overcome the increased friction due to cold weather.

30 My invention makes the throttle control entirely automatic during starting and eliminates the hazards due to the human element in manually controlled systems.

- 35 The object of my invention is to provide a device that will improve the starting of internal combustion engines.

40 Still further features of the invention consist in certain novel features of construction, combinations and arrangements of parts hereinafter described and claimed, the advantages of which will be obvious to those skilled in the art from the following description.

- 45 Fig. 1 is a diagrammatic view showing how my

invention can be used to control the throttle opening of a carburetor.

Fig. 2 is a sectional view taken along the line 2—2 of Fig. 1.

Figure 3 is a diagrammatic view of an automatic starting switch in combinative association with the device constituting my invention.

Referring to Fig. 1, 1 is a storage battery and 2 is an electric motor used for starting. The partially sectioned carburetor 4 is used to mix fuel and air for proper combustion. A starting switch 3 opens and closes the circuit between the storage battery 1 and the starting motor 2. The sectioned solenoid 5 has a plunger 6, which is pivotally connected by link 7 to lever 8. Lever 8 is freely mounted on throttle shaft 11 and engages with lug 10 on the rigid throttle lever 12. Throttle control lever 12 is rigidly attached to shaft 11 which carries throttle valve 9. 13 is a diagrammatic view of an intake manifold and 14 is a diagrammatic representation of an internal combustion engine.

When the switch 3 is closed electrical current is supplied to starting motor 2 and solenoid 5. The plunger 6 then moves upward and operates link 7 causing lever 8 to move in a clockwise direction. As lever 8 is turned in this direction it engages with lug 10 on lever 12 thus opening the throttle valve 9 a predetermined amount. Throttle valve 9 can be opened further independent of lever 8 by manipulating the accelerator pedal or hand throttle lever both of which are operatively connected to the lever 12.

As soon as the starting switch 3 is open current ceases to pass through the solenoid rendering it 35 inoperative and permitting the plunger 6 thereof to fall to its normal position. This allows the normal throttle closing means to predominate and the throttle closes to normal idling position. It is thus apparent that the solenoid is enabled to 40 operate the throttle valve for proper operating efficiency independent of the usual foot or hand operated mechanism.

Inasmuch as solenoids are made with various 45 operating characteristics, some being of the quick acting type and others of the lag or slow operating class, a solenoid can be chosen of such predetermined operating characteristics as to produce a desired differential between the time of operation of the motor and valve. Thus by a suitable 50 choice of solenoid the valve can be opened before the engine is started under the influence of the motor.

55 My invention can be readily adapted for use with so-called automatic starters which are set

into operation by turning on the ignition switch on the dashboard. Such devices are in general commercial use and have, as is well known, a movable element actuated by the ignition circuit for closing the starting circuit, this movable element, which is usually the plunger of a solenoid, bringing the contacts of the starting switch into engagement. By simply connecting the link 7 of my device to this movable element or solenoid, 5 instead of to the plunger 6 of the solenoid 5, my device will operate as above described. The movable element actuates the link 7, which in turn actuates the throttle valve as aforesaid. With such an arrangement it is necessary that the link 7 be a flexible shaft, such as a Bowden wire.

Specifically, referring to Figure 3, the ignition switch 15 generally positioned on the dashboard and constituting part of the circuit containing the winding 16 about the solenoid 17, is electrically connected to the stationary contact terminal 18. The contact 19 is affixed to the plunger of the said solenoid 17 and is adapted for simultaneous operative contacting engagement with the terminals 18 and 20, the latter being contained within the starting motor circuit. Suitably secured to solenoid 17 is one end of the Bowden wire or flexible shaft 7a equivalent to the link 7 of Figure 1,—the other end being connected to the throttle valve through the equivalent 10 of the lever 8, lug 10, shaft 11 and lever 12.

In the operation of the device of Figure 3, when the switch 15 is closed, the solenoid 17 will be drawn to the right to close the circuit via the contact elements 18, 19 and 20 through the starting motor 21, and at the same time operatively move the link 7a to actuate the throttle valve with which it is connected.

While I have described several embodiments of my invention, I do not wish to be limited to the particular forms shown and described as it will be apparent that many modifications therein can be made without departing from the scope of my invention as set forth in the appended claims.

Having thus described my invention, what I claim is:

1. In combination with the carburetor, intake manifold and starting motor of an internal combustion engine, a throttle valve within said manifold, electro-mechanical means operatively connected with said valve, a switch electrically connected to said motor and electro-mechanical means, means associated with said latter means

and the valve for effecting a partial actuation thereof upon an operative movement of the electro-mechanical means, and mechanical means independent of said electro-mechanical means and adapted, upon a manipulation thereof, to actuate the valve through its complete operative path.

2. In combination with the carburetor, mixing passage and starting motor of an internal combustion engine, a throttle valve within said passage, a solenoid operatively connected with said valve, unitary switching means electrically connected to said motor and solenoid and adapted, upon a manipulation thereof, to effect the starting of the motor and energizing of the solenoid; 10 said solenoid being adapted when energized, to partially open said valve a predetermined amount; means to return the solenoid to its normal inoperative condition when de-energized; and means mechanically connected to said valve 15 and adapted, upon a manipulation thereof, to independently actuate the valve.

3. In combination with the carburetor, mixing passage and starting motor of an internal combustion engine, a throttle valve within said passage, electro-mechanical means of predetermined magnetic characteristics operatively connected to said valve and adapted, upon the energizing thereof, to partially open the valve a predetermined amount; the motor and electro-mechanical means being in independent circuits electrically connected to a single switch and source of current supply; and mechanical means operatively connected to said valve and adapted, upon a manipulation thereof, to independently actuate the valve.

4. In combination with the carburetor, intake manifold and starting motor of an internal combustion engine, a throttle control comprising, in combination, a valve operatively positioned within said manifold, a solenoid the circuit of which is in parallel with that of the motor, a switch and source of current supply common to both the solenoid and motor circuits, a throttle shaft for said valve, a link pivotally connected to the plunger 45 of the solenoid, a lever rotatably mounted over said shaft and pivotally connected to said link, a throttle lever affixed to said shaft, and a lug on said throttle lever adapted for operative engagement with said first-mentioned lever.

CHESTER A. KILLMEYER.
